UNITED STATES PATENT OFFICE

2,532,771

LOOSE-LEAF BINDER

Louis William Johnstone, Warlingham, and
Charles Edward Gilbert, Chipstead, England,
assignors to Bernard Bercovitz, Toronto, Ontario, Canada

Application April 10, 1946, Serial No. 660,954
In Great Britain February 8, 1945

Section 1, Public Law 690, August 8, 1946
Patent expires February 8, 1965

2 Claims. (Cl. 129—18)

1

This invention relates to books, catalogues, files, card indices, and the like, and more particularly to what are known as loose leaf binders or any other collection, group, or plurality of documents, papers, cards, tablets or the like, hereinafter referred to as sheets, held together along one edge so that the contents may be accessible and where it is required that one or more of the sheets may be readily detached or inserted.

For example, manufacturers and marketing organisations selling a variety of goods the nature or price of which is constantly changing, find it expedient to publish such a book or catalogue describing their commodities and this invention is particularly efficacious when applied to books or catalogues for such a purpose. The construction of devices to perform the above described function has in the past involved the use of relatively expensive covers with metal fittings and other elaborated variations of the bookbinder's craft, and the object of this invention is to provide a simple device for the retention of sheets and to facilitate their insertion or withdrawal and to occupy the minimum space beyond the bulk of the sheets.

The following is a description of one embodiment of the invention, reference being made to the accompanying drawings, in which:

Figure 1 is an exploded perspective view of the various parts of the binder;

Figure 2 shows the parts of Figure 1 assembled to provide the spine and sliding member shown separated from one another;

Figure 3 is a perspective view showing the sliding member assembled with the spine and in a position to receive a stack of sheets;

Figure 4 is a perspective view showing the stack of sheets assembled in the binder, as shown in the previous figures.

Referring to the construction shown in the drawings, the spine of the binder may be built up from an inner channel-shaped member 10 having its side walls cut away at each end, as indicated at 11 and 12. The cut-away portion 11 is arranged to be filled by a channelled filling piece 13, the bottom wall of which, when in position in the channel member 10, provides a web 14 extending between the side walls of the other member 10. The inner channel member 10 is embraced by an outer channel member 9 which extends from the cut-away portion 12 to the other end of the member 10, and serves to hold the filling piece 13 in position. A sliding member is provided in the form of an outer sliding

2

channel 15, in which is nested an inner channel filling member 16 which is so secured in position that the bottom wall thereof 17 is spaced away from the bottom wall of the outer channel 15 and forms a web. This composite sliding member is arranged slidably to engage the reduced extension of the channel member 10 provided by the cut-away portion 12 so that the extension lies between the web 17 and the bottom wall 18 of the sliding member. As will be seen from Figure 3, this binder is arranged to hold in position a stack of sheets having a tongue 19 along one side thereof which is under-cut at 20 to provide overlying portions 21. When it is required to insert the sheets the slide is moved into the position shown in Figure 3 so that the distance between the edges of the web portions 14 and 17 is such as to enable the tongue 19 to be inserted between them. The slide is then moved into the position shown in Figure 4, in which the webs 14 and 17 move into the under-cut portion 20. The sliding member 15 is prevented from detachment from the part 9 by means of a tethering tape 22. All the above parts may be formed from cardboard, vulcanised fibre, or plastic sheet.

We claim:

1. A binder adapted to retain a plurality of sheets having along one side thereof at least one tongue undercut to provide overhanging portions on each side thereof, which binder comprises an inner channel-shaped member having its side flanges partially cut away at each end, a channelled filling piece arranged in the cut-away portion at one end of said inner channel-shaped member, the back of said channelled filling piece forming a web extending between the cutaway flanges of said inner channel-shaped member at said end and spaced from the back wall thereof, an outer channel-shaped member embracing said inner channel-shaped member and said channelled filling piece and extending short of the cutaway portion at the other end of said inner channel-shaped member, said outer channel-shaped member serving to hold said channelled filler piece in the cutaway portion of said inner channel-shaped member, and a sliding channel-shaped member comprising inner and outer channels, said inner channel being so secured to said outer channel that the back wall of said inner channel is spaced away from the back wall of said outer channel and forms a web extending between the flanges of said outer channel whereby said sliding channel-shaped member is adapted to slidably en-

gage the cutaway portion of said inner channel-shaped member at said other end.

2. A binder adapted to retain a plurality of sheets having along one side thereof at least one tongue undercut to provide overhanging portions on each side thereof, which binder comprises an inner channel-shaped member having its side flanges partially cut away at each end, a channelled filling piece arranged in the cutaway portion at one end of said inner channel-shaped member, the back of said channelled filling piece forming a web extending between the cutaway flanges of said inner channel-shaped member at said end and spaced from the back wall thereof, an outer channel-shaped member embracing said inner channel-shaped member and said channelled filling piece and extending short of the cutaway portion at the other end of said inner channel-shaped member, said outer channel-shaped member serving to hold said channelled filler piece in the cutaway portion of said inner channel-shaped member, a sliding channel-shaped member comprising inner and outer channels, said inner channel being so secured to said outer channel that the back wall of said inner channel is spaced away from the back wall of said outer channel and forms a web extending between the flanges of

5 said outer channel whereby said sliding channel-shaped member is adapted to slidably engage the cutaway portion of said inner channel-shaped member at said other end, and a flexible tether secured between the outer channel-shaped member and the sliding channel shaped member to limit longitudinal movement therebetween.
